CALENDAR

Hilario V. Ylio, Brooklyn, N. Y.

Application January 16, 1941, Serial No. 374,648

3 Claims. (Cl. 40—112)

This invention relates to new and useful improvements in a new day calendar.

More specifically, the invention proposes the construction of a calendar characterized by a nickel plated hollow casing having a front wall provided with several window openings behind which drums are rotatively supported and provided with an exterior means arranged in a manner to facilitate the rotation of the drums to expose portions thereof in the window openings.

Still further it is proposed to imprint the drums with a certain calendar material for the purpose of indicating the day of the week, the day of the month, the month of the year, and the year in a manner to permit the drums to be selectively aligned for indicating a predetermined day.

Still further it is proposed to individually mount the drums upon rotatively supported shafts which also carry complementary wheels projected through other openings formed in the front wall of said casing in a manner to facilitate the rotation of the shafts to change the exposed portions of the drums.

Still further it is proposed to provide a means for releasably holding the drums in various fixed positions in which the imprinted matter of the drums will be properly aligned with the window openings.

A further object of this invention proposes the provision of a flat edge portion on each of the control wheels which is adapted to be brought into position with the front wall of the casing in a manner to prevent the projection and exposure of portions of these wheels when not being used to shift the position of the drums.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevational view of a new day calendar constructed in accordance with this invention.

Fig. 2 is a vertical sectional view taken substantially on the line 2—2 of Fig. 1.

Fig. 3 is a horizontal sectional view taken on the line 3—3 of Fig. 1.

Fig. 4 is a horizontal sectional view taken on the line 4—4 of Fig. 1.

Fig. 5 is a view similar to a portion of Fig. 1

but illustrating a modification of the invention.

Fig. 6 is a vertical sectional view taken on the line 6—6 of Fig. 5.

The new day calendar, according to this invention, includes a hollow nickel plated casing 10. This casing is characterized by a tubular shell 11 having its axis extended substantially horizontal to a surface upon which the device is to be rested. The back of the tubular shell is closed by means of a back wall 12 and a front wall 13 closes the front of the tubular shell 11. These walls 12 and 13 are fixedly maintained in position by means of screws 14. The front wall 13 is formed with a plurality of window openings 15 in predetermined spaced positions with relation to each other. There is one window opening 15^a at a point above the center of the front wall 13 and a plurality of window openings 15^b arranged one adjacent each other on a line extending substantially through the center of the front wall. The window openings 15^b are preferably four in number.

A tubular rod 16 is extended horizontally to the rear of the window opening 15^a and a similar tubular rod 17 is extended horizontally to the rear of the line of window openings 15^b. These tubular rods 16 and 17 are adapted to act as supporting axles and are themselves fixedly supported in brackets 18 provided with openings 25 for receiving the ends of these tubular rods. The brackets 18 extend rearwards and are provided with pairs of bosses 18^a through which set screws 19 are adapted to pass. These set screws 19 also threadedly engage the back wall 12 of the hollow casing for fixedly attaching the brackets 18 to this back wall.

The tubular rod 16 carries a drum 20 in an aligned position with the window opening 15^a. The drum 20 is imprinted upon its face with calendar material and more preferably, the days of the week arranged in chronological order for successively exposing the days of the week to the center opening 15^a as the drum is progressively rotated. The drum 20 is fixed to a tubular shaft 21 which is rotatively positioned on the rod 16. One end of the tubular shaft 21 is provided with a control wheel 22 which extends through an opening 23 formed in the front wall 13 of the casing. The wheel 22 is provided with 40 a knurled periphery which permits the same to be frictionally engaged by one's finger for rotation in an upward direction to progressively expose the days of the week imprinted on the drum 20.

There is a drum 24 provided for each of

the window openings 15^b. Each of these drums 24 similar to the drum 20 is imprinted upon its face with calendar material. In Fig. 3, starting from the left to the right, the first drum 24 is imprinted with the months of the year arranged in chronological order. The next drum to the right is imprinted upon its face in chronological order with the numbers 1, 2, 3-1, 2, 3-blank. The next drum to the right is imprinted upon its face with the numbers from zero to 9, and the last drum to the right is imprinted with twelve year numbers arranged in chronological order. Each of the drums 24 is fixedly attached to a tubular shaft 25 which rotatively engages the tubular rod 17 which acts as a support therefor. The tubular shafts 25 have certain projected portions upon which control wheels 26 are fixedly mounted. These control wheels 26 are projected through complementary openings 27 formed to the right and left of the line of window openings 15 and in the front wall 13 of the casing. It is thus possible to selectively rotate the wheels 26 to rotate their complementary shafts 25 and drums 24 carried by these shafts to align different portions of the drums with the window openings 15^b.

A means is provided for releasably holding the drums in various fixed positions in which the calendar material imprinted thereon will be properly aligned with the window openings 15^a and 15^b. This means is alike for all the drums 20 and 24 and is characterized by a ratchet wheel 28 each of which is provided with a plurality of teeth. The teeth formed in these ratchet wheels correspond in number to the number of impressions made on the faces of their respective drums. That is, the drum 20 which is used to indicate the day of the week has seven impressions and its respective ratchet wheel is preferably provided with seven teeth. The drum 24 for indicating the month of the year is provided with twelve impressions and its respective ratchet wheel 28 has twelve teeth. Each of the drums 24 has its respective ratchet wheel formed in a similar manner.

A pawl 29 is extended rearwards from the ratchet wheels 28 and is pivotally supported upon a bracket 30 which is mounted upon the rear wall 12 of the casing. Each of the brackets 30 is provided with bosses through which set screws 31 are engaged. These set screws 31 also threadedly engage the rear wall 12 of the casing for fixedly maintaining the brackets in position thereon. Each of the pawls 29 has a hook portion 29^a which engages the teeth of its respective ratchet wheel 28.

A leaf spring 32 is fixedly mounted upon the top of the bracket 30 by means of a screw 33. The free end of the leaf spring 32 bears against the free end of the pawl 29 for urging the pawl into a position in which its hook portion 29^a will be engaged with the teeth of its respective ratchet wheel 28. The ratchet teeth and the hook portions 29^a are arranged in such a manner as to limit rotation of the drums 24 in a clockwise direction and restrain movement in the opposite direction.

The operation of this form of the device is as follows:

After the new day calendar has been properly assembled it is possible to indicate any predetermined day of the year by rotating the proper wheels 22 or 26 to cause the respective drums 20 or 24 to rotate therewith and bring the proper predetermined calendar material in position with

relation to the window openings 15^a and 15^b. As the wheels 28 are turned the pawls 29 which engage the teeth of the ratchet wheels 28 will slip over these teeth permitting a free rotation in a clockwise direction and will also limit rotation in the opposite direction and act to hold the drums in a position in which the respective calendar material will be properly aligned with the window openings.

According to the modification of the invention shown in Figs. 5 and 6 the construction of the new day calendar is similar to that previously described except for the provision of a means for individually rotatively mounting the wheels 26' on the respective shafts to which their drums are attached. In this form of the invention each of the wheels 26' is formed with a flat edge portion 26^a which when aligned with the face of the front wall 13 of the casing prevents the wheel from having a portion projected beyond this face.

Means is provided for locking the wheels 26' to their respective shafts when turned in a clockwise direction and for freeing these shafts when turned in an anti-clockwise direction to turn independently of its respective shaft permitting its flat side to be aligned with the face of the casing irrespective of the position of its drum. This means comprises a clutch characterized by a pair of oppositely disposed balls 35 located within cutouts 36 formed in the inside surface of the wheels 26' and adjacent their respective shafts.

The openings 36 are of a particular nature and have an enlarged end 36^a and a reduced end 36^b. When the wheels 26' are rotated in a clockwise direction the balls 35 will be moved to engage within the reduced portions 36^b of the openings and act to lock the wheels 26' to their respective shafts to cause the same to be turned. However, when an attempt is made to rotate the wheels 26' in an anti-clockwise direction the balls 35 will be positioned within the enlarged portions 36^a of the openings 36 to permit the wheels 26' to be turned independently of their respective shafts. When the wheels 26' have their flat edge portions 26^a aligned with the face of the casing as shown in Fig. 6, and to start rotation thereof in a clockwise direction, it is merely necessary to press inwards upon the top of this flat portion which will cause the bottom to be exposed to be conveniently gripped in one's fingers.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A new day calendar, comprising a casing having spaced front and rear walls, horizontally spaced brackets mounted on the inside face of said rear wall and projected into the vicinity of the inside face of said front wall, a tubular shaft, a drum fixedly mounted on one end of said shaft and provided on its periphery with printed matter viewable through a window opening formed in the front wall of said casing, a wheel mounted on the other end of said shaft and aligned with another opening formed in said front wall by which said shaft may be turned to likewise turn said drum, and a rod fixedly mounted between the front ends of said brackets, and said tubular shaft being rotatively supported on said rod be-

tween said brackets permitting rotation thereof, said wheel being free upon the end of said tubular shaft and having a flat side projected into its respective opening and flush with the face of said front wall forming a flat front wall on said casing free of projecting portions, and means for locking said wheel to its shaft when turned in one direction to simultaneously turn said shaft and drum, whereby when said wheel is turned in the opposite direction it rotates independently of said shaft and drum so that its flat side may be aligned with its respective opening regardless of the position in which said shaft and drum is located.

2. A new day calendar, comprising a casing having spaced front and rear walls, horizontally spaced brackets mounted on the inside face of said rear wall and projected into the vicinity of the inside face of said front wall, a tubular shaft, a drum fixedly mounted on one end of said shaft and provided on its periphery with printed matter viewable through a window opening formed in the front wall of said casing, a wheel mounted on the other end of said shaft and aligned with another opening formed in said front wall by which said shaft may be turned to likewise turn said drum, and a rod fixedly mounted between the front ends of said brackets, and said tubular shaft being rotatively supported on said rod between said brackets permitting rotation thereof, said wheel being free upon the end of said tubular shaft and having a flat side projected into its respective opening and flush with the face of said front wall forming a flat front wall on said casing free of projecting portions, and means for locking said wheel to its shaft when turned in one direction to simultaneously turn said shaft and drum, whereby when said wheel is turned in the opposite direction it rotates independently of said shaft and drum so that its flat side may be aligned with its respective opening regardless of the position in which said shaft and drum is located, comprising a ball located within a

triangularly shaped opening extended inwards from the central opening of said wheel and disposed adjacent said shaft.

3. A new day calendar, comprising a casing having spaced front and rear walls, horizontally spaced brackets mounted on the inside face of said rear wall and projected into the vicinity of the inside face of said front wall, a tubular shaft, a drum fixedly mounted on one end of said shaft and provided on its periphery with printed matter viewable through a window opening formed in the front wall of said casing, a wheel mounted on the other end of said shaft and aligned with another opening formed in said front wall by which said shaft may be turned to likewise turn said drum, and a rod fixedly mounted between the front ends of said brackets, and said tubular shaft being rotatively supported on said rod between said brackets permitting rotation thereof, said wheel being free upon the end of said tubular shaft and having a flat side projected into its respective opening and flush with the face of said front wall forming a flat front wall on said casing free of projecting portions, and means for locking said wheel to its shaft when turned in one direction to simultaneously turn said shaft and drum, whereby when said wheel is turned in the opposite direction it rotates independently of said shaft and drum so that its flat side may be aligned with its respective opening regardless of the position in which said shaft and drum is located, comprising a ball located within a triangularly shaped opening extended inwards from the central opening of said wheel and disposed adjacent said shaft, said triangular opening having a large end greater in depth than the diameter of said ball and a small end having a depth less than the diameter of said ball, causing the wheel to become locked to said shaft when said ball is wedged between the small end of said triangular opening and said shaft.

HILARIO V. YLIO.
